FAULT DETECTOR FOR PAPER WEBS

Pentti Kalervo Mannonen, 6 D 51 Kuohukuja,
01600 Myyrmaki, Finland

Filed July 2, 1973, Ser. No. 375,523

Term of patent 14 years

Int. Cl. D10—05

U.S. Cl. D10—46

FIG. I

FIG. 2

FIG. 1 is a top, side and end perspective view of a fault detector for paper webs showing my new design;
FIG. 2 is a bottom and opposite side perspective view thereof.

I claim:
The ornamental design for a fault detector for paper webs, as shown.
